Application filed April 4, 1892. Serial No. 427,763. Term of patent 7 years.

To all whom it may concern:

Be it known that I, ANTON WEBER, a citizen of the United States, and a resident of Philadelphia, Pennsylvania, have invented a new and original Design for Silversmiths' Stock, 5 of which the following is a specification.

My design for silversmiths' stock is clearly illustrated in the accompanying drawing.

The design consists of a serpentine stem *a*, 10 from which extend scroll-like branches, some of which have representations of berries *b*. Inclosed by the stem and branches are the rosette *d* and the conventionalized floral rep-

resentation *e*, these being the distinctive features of the design. 15

I claim—

The design for silversmiths' stock, substantially as described, and as shown in the accompanying drawing.

In testimony whereof I have signed my name to this specification in the presence of two subscribing witnesses.

ANTON WEBER.
